CONCEALED CARPET TACKING TAPE

Ted W. Bernhardt, San Fernando, Calif.

Application June 21, 1938, Serial No. 214,967

2 Claims. (Cl. 16—16)

This invention relates to carpeting and more particularly to a concealed tacking tape for same.

The general object of the invention is to secure a tacking tape to the under side of the edge 5 of a carpet, this tape to be invisible and adapted for the attachment of tacks thereto which will also be invisible and yet will serve to secure the edges of a carpet to the floor. This and other objects will be apparent and be brought out more fully in the following specification, reference being had to the accompanying drawing wherein

Fig. 1 is the fragmentary view showing the underside of a carpet and a portion of the tacking tape partially secured thereto, and

Fig. 2 is a view of same showing the tacking tape completely secured to the carpet and

Fig. 3 is a vertical section view of the same as it would appear in use.

Referring more particularly to the drawing, I 20 show a fragmentary portion of a carpet 5 having a fabric portion 6 and nap 7 and having a linear edge portion 8 which is to be secured to the floor adjacent a wall or otherwise. The tacking tape comprising my invention consists of a blind 25 binding tape 9 which may be blind stitched along an edge 10 to the edge 8 or carpet fabric. A cover tape 11 is suitably secured as by sewing or cementing to tape 9, and positions a plurality of tacks 12 which extend through tape 9. The edge 30 13 of tape 9 is secured to fabric 6 preferably by cementing or otherwise and the tacking tape is thereupon complete. The tacks 12 may now be driven into the floor by hammering through the carpet and it will be apparent that the edge of

the carpet can be laid along a wall or baseboard and will be securely held and that no tack heads will be visible. It will also be apparent that the blind stitching along the edge 8 of the fabric will also serve to keep the nap of the carpet from 5 coming out.

It will be understood that the tacking tape comprising my invention may be made in colors similar to colors of the carpet and that it may be secured to the carpet in other means substantially equivalent to those shown herein above.

Having described my invention, what I claim is:

1. Tacking tape as described comprising a tape strip adapted to have an edge secured to an edge 15 of a carpet and having an opposite edge secured to said carpet along a line spaced from said carpet edge, a second tape strip secured to and along said first strip adjacent said carpet and a plurality of tacks extending through said first 20 strip and having the head portions thereof between said strips.

2. Tacking tape as described comprising a tape strip adapted to have an edge secured to an edge of a carpet and having an opposite edge secured 25 to said carpet along a line spaced from said carpet edge, a second tape strip secured by adhesive means substantially throughout the area thereof to and along said first strip adjacent said carpet and a plurality of tacks extending through 30 said first strip and having the head portions thereof between said strips.

TED W. BERNHARDT.
